UNITED STATES PATENT OFFICE

2,447,421

SWINGING WINDOW CONSTRUCTION

Charles G. Nachtrieb, Streator, Ill.

Application April 5, 1944, Serial No. 529,571

7 Claims. (Cl. 20—42)

1

This invention relates in general to window construction and more particularly to a window construction in which one or more sashes may be swung in relation to the window frame to render both sides of a sash accessible from one side of the frame.

An object of this invention is to provide compact, safe, simple and efficient means providing for the swinging of a window sash in relation to its frame quickly and conveniently to enable access to both sides of the sash from one side of the window so that it can be cleaned, painted, and repaired without leaning or climbing out of the window on the part of an operator.

Another object of this invention is to provide novel means in a swinging window construction for conveniently, effectively and expeditiously connecting and disconnecting a window sash and counterbalancing means therefor to enable the sash to be secured in its frame for normal sliding movement in relation thereto, disconnected and swung in one direction to an open position while remaining slidable in relation to the frame, and thereafter restored to normal slidable relation with the frame.

A further object of the invention includes the provision of novel means in a double-hung swinging window construction for securing one or more sashes in normal slidable relation with a frame, disconnecting one or more of the sashes from their respective counterbalancing means, enabling sequential swinging of the sashes in relation to the frame to provide access to both sides of the sashes from one side of the frame while the sashes remain slidable in relation to the frame, returning the sashes to normal slidable relation with the frame, connecting them with their respective counterbalancing means, and securing them in normal slidable relation with the frame.

Other objects of the invention include the provision of novel means in a window construction for disconnectably connecting a sash and the counterbalancing means associated therewith and for maintaining the counterbalancing means in adjusted position in relation to the frame and the sash while the sash and the counterbalancing means are disconnected. Additional objects, advantages and capabilities inherent in this invention will become readily apparent from the description thereof which follows.

This invention further resides in the combination, construction and arrangement of parts illustrated in the accompanying drawings, and while there is shown therein preferred embodiments of the invention, it is to be understood that the

2

same are susceptible of modification and change without departing from the spirit of the invention.

The accompanying drawings illustrate a selected embodiment of the invention, and the views therein are as follows:

Fig. 1 is an elevational view of a double-hung swinging window construction embodying the invention with upper and lower sashes secured in closed position and in sliding relation with the window frame;

Fig. 2 is an elevational view of the construction shown in Fig. 1 with the lower sash in a position of adjustment preliminary to the swinging of the sash;

Fig. 3 is an elevational view of the same construction with the lower sash in a second position of adjustment and disconnected from associated counterbalancing means preliminary to the swinging of the sash in relation to the frame;

Fig. 4 is an elevational view of the same construction with the lower sash swung to an intermediate open position in relation to the frame;

Fig. 5 is an elevational view of the same construction with the lower sash swung to fully open position and the upper sash in a position of adjustment preliminary to the swinging of it in relation to the frame;

Fig. 6 is an elevational view of the same construction with the lower sash swung to fully open position and the upper sash swung to an intermediate position in relation to the frame;

Fig. 7 is a detail view, partially in section, showing disconnectible means for connecting a sash and associated counterbalancing means;

Figure 8 is a sectional view taken substantially along the line 8—8 in Fig. 7;

Fig. 9 is a detail view, partially in section, showing the disconnectible means for connecting a sash and associated counterbalancing means with the parts in disconnected position, as in Fig. 3;

Fig. 10 is a sectional view taken along the line 10—10 of Fig. 1, with both sashes shown in intermediate swung position, partially broken away;

Fig. 11 is a detail view of parts of the invention shown in Fig. 7;

Fig. 12 is a detail view of a modified form of a portion of the invention shown in Fig. 7.

The particular window construction herein disclosed for the purpose of illustrating the invention comprises a frame 11 which may be of wood, metal or other suitable material, having upper and lower sashes 12 and 13 slidably and pivotally mounted therein in parallel spaced relation

with one another and in operative association with counterbalancing means comprising counterweights 14, sash cords 15 and pulleys 16 which are rotatably mounted on the frame 11. The frame is provided with spaced guides 17, preferably of metal, arranged adjacent the corresponding edges of the sashes 12 and 13 and in co-operative relation with spaced hinge members 18, which are secured to the sashes at the adjacent edges thereof. The hinge members 18 are provided with shoes 19 which are arranged for cooperative sliding relation with the guides 17. As shown in Fig. 10 the arrangement and configuration of the guides 17, the hinge members 18, and the shoes 19 are such as to provide for 10 swinging and sliding movement of the sash in relation to the frame. To this end the guide may be in the form of an I or H and the shoe conformed to engage opposite faces of adjacent portions of the guide in slidable relation therewith.

Cooperating means are provided on each sash and the sash cord of one of its associated counterbalancing means for disconnectably connecting the sash and the counterbalancing means, the sash cord of the other counterbalancing means being secured adjacent an end thereof to the sash, preferably at an edge thereof in spaced relation with the connection of the first mentioned sash cord with the sash. The cooperating means include a supporting or housing member 20 carrying a lever member 21 mounted adjacent one end thereof for pivotal movement in a plane normal to the axis of the pivot pin 22 which is received in aligned openings in the housing member and the lever member. The lever member 21 is provided with an opening 23 arranged in spaced relation with the pin 22 for pivotally receiving a hook portion 24 of a connecting link 25, thereby forming an actuating arm on the lever between the pivot pin 22 and the opening 23. The link has a hook portion 26 disposed in spaced relation with the portion 24 and arranged to be detachably received in an opening 27 in an end portion of a connecting member 28 which is secured to the sash cord 15 adjacent one end thereof. The lever member 21 is provided adjacent its end portion remote from the pin 22 and the opening 23 with opposite latching portions 30 and 31.

The housing member or carriage 20 is generally U-shaped in cross-section, having generally rectangular opposite wall portions 32 between which the lever member 21 and the link 25 are received, the latching portions 30 and 31 extending outwardly from one end of the housing member. The housing member 20 is conformed and arranged to be slidably received in the way 33 which is provided in the adjacent wall of the frame 11 with the intermediate wall 34 of the housing member preferably facing the way 33. Keeper means in the form of a slot 35 is provided within the way 33 in the frame 11 for receiving the latching portion 30 of the lever member 21.

Each sash is provided with a cut away portion or recess 36 arranged in cooperative spaced relation with the corresponding way 33 and the lever member 21 when the sash is in normal position in slidable relation with the frame. The cut away portion 36 has an elongated portion 50 arranged to receive the housing member 20 and a generally rectangular extension 51 arranged to receive the latching portion 31 of the lever member 21 and means for operating the lever

member 21. The cut away portion 50 is co-extensive at one end thereof with an end portion of the sash to enable withdrawal of the housing member 20 and the lever member 21 from the 5 cut away portion 50 by sliding movement of the sash, as illustrated in Fig. 9.

The means for operating the lever member 21 may be in the form of a slide member 37 provided with an angulated portion 38 having a surface 39 arranged to engage a corresponding surface 40 provided on the latching portion 31 of the lever member 21. The slide member 37 is provided with spaced arms 41 and 42 arranged in cooperative spaced relation with a movable arm 43 rigidly mounted at one end thereof on a shaft 44 which is rotatable in the sash. The shaft 44 is rotatable by means of a lever 45 or a knob 46 secured on its outer end; or may be provided with a squared opening or slot 47 for receiving a removable key 48 for rotating it. In the form shown in Figs. 1 to 6 inclusive, the lever 45 is a relatively thin, flat member having a surface arranged in slightly spaced relation with an adjacent surface of the sash. In the form shown in Fig. 8, the sash has a cut away portion 49 in which the knob 46 is turnably inset. The slide member 37, the arm 43, and the shaft 44 may be operatively mounted in a casing 29 conforming with the cut away portion 36 and secured therein by means of screws 29a.

The arrangement of the slide member 37, the arm 43 and the shaft 44 is such that upon rotating the shaft 44 by means of the lever 45, the knob 46 or the key 48, from the position shown in Fig. 7 in an anti-clockwise direction, the slide member 37 will be shifted to the position shown in Fig. 9 and upon reverse movement of the shaft 44 the slide member 37 will be returned from the position shown in Fig. 9 to the position shown in Fig. 40 7.

When the parts are in cooperative position, as in Fig. 7, such movements result in corresponding movements of the lever member 21, which is normally urged in a clockwise direction in relation to the axis of the pin 22, viewing Fig. 7, by the operation of the counterbalancing means connected with the lever member through the link 25. As the slide member 37 is moved to the right from the position shown in Fig. 9, the surface or keeper 39 of the portion 38 engages the surface 40 of the latching portion 31 and the lever member 21 is shifted against the action of the counterbalancing means in anti-clockwise direction to the position shown in Fig. 7 in which the latching portion 31 engages adjacent surfaces of the cut away portion 50 or keeper 51, and the latching portion 30 engages adjacent surfaces of the way 33, thus operatively connecting the counterbalancing means and the sash and securing the sash against swinging movement in relation to the frame. This relation is maintained until the slide member 37 is moved in the opposite direction to release the latching portion 31. The operation of the counterbalancing means then causes pivotal movement of the lever member 21 about the pin 22

65 in a clockwise direction and latching engagement of the latching portion 30 with the keeper means or slot 35 in the frame, as shown in Fig. 9. This latching engagement of the portion 30 with the slot 35 is maintained by the operation of the counterbalancing means until the surface 39 is again brought into operative engagement with the surface 40 and the lever member 21 shifted in an anti-clockwise direction as above described.

When the lever member 21 is in the position shown in Fig. 9 the sash 13 may be slid from the

position shown in Figs. 2 and 7 to that shown in Figs. 3 and 9 and then swung in relation to the frame to the positions shown in Figs. 4, 5 and 6. When the sash 13 has been thus swung to the position shown in Fig. 5, the sash 12 may be similarly swung to the position shown in Fig. 6 by repetition of the steps described in respect to the sash 13. Both sashes remain slideable in relation to the frame when in swing position.

The sashes may be returned to locked position 10 in slideable relation with the frame by a reversal of the steps described.

Suitable guides or stops 52, 53 to limit swinging movement of the sashes, respectively, in one direction are preferably provided in the frame, as shown in Fig. 10. A frontal stop or guide 57 is provided adjacent the bottom of the frame, as shown in Fig. 1, to prevent swinging movement of the sash 13 in its lowermost position. In order to clear this stop, it is necessary that the sash be raised to the position shown in Figs. 3 and 6. The sashes also are preferably provided with cut away portions 54 in the edges adjacent the slides 17 for receiving the sash cords 15 secured therein. Weather stripping may be provided in generally conventional manner, but preferably being arranged as indicated at 55, 56, in Fig. 10, cut away portions 58 being provided in the sashes to receive it.

The operation of a swinging window construction embodying the invention may be described as follows:

With the parts in the position shown in Fig. 1, the lever member 21 and the slide member 37 being in the adjusted relation shown in Figs. 7 and 8, the member 45, the knob 46, or the key 48, as the case may be, of the sash 13, is operated to rotate the shaft 44 and shift the slide member 37 to the position shown in Fig. 9, the member 45 being shifted to the position shown in Fig. 2. The sash 13 is then slid upwardly in relation to the frame to the position shown in Figs. 2, 7 and 8, in which the latching portion 30 and the slot 35 are in register. Upon such operation of the slide member and the sash, the lever member 21 is shifted from the position shown in Fig. 7 to that shown in Figs. 3 and 9 by operation of the counterbalancing means, thus disconnecting the counterbalancing means from the sash and enabling the sash 13 to be slid downwardly to withdraw the housing 20 and lever member from the cut away portion 50. In this connection it should be observed that the shifting of the lever member 21 occurs automatically upon the coming into register of the latching portion 30 with the slot 35. Whereupon the sash may be manually swung with relation to the frame to the position shown in Fig. 5. Thereafter similar steps may be followed in respect to the sash 12.

When it is desired to return the sashes to normal slideable relation in the frame, the sash 12 is swung back into the frame and raised to the position shown in Fig. 5. The member 45 is then operated to shift the slide member 37 from the position shown in Fig. 9 to that shown in Fig. 7 thereby connecting the sash 12 with its associated counterbalancing means and locking it in the frame in slideable relation therewith. The sash 13 may be returned to normal slideable relation with the frame in like manner.

Changes may be made in the form, construction and arrangement of the parts without departing from the spirit of the invention, and the right is hereby reserved to make all such changes

as fairly fall within the scope of the following claims.

The invention is hereby claimed as follows:

5. In a window construction, the combination, with a frame, of keeper means on the frame, a sash mounted in the frame for swinging and sliding movement in relation to the frame, keeper means on the sash, counterbalancing means mounted on the frame and connecting means to detachably connect the counterbalancing means with the sash comprising, a support, a lever member pivotally mounted adjacent one end thereof on the support for movement in a plane normal to the pivotal axis of the member, the lever member having opposite latching portions adjacent an end thereof remote from the said pivotal axis, an arm on the lever member and arranged in spaced relation, about said pivotal axis, with respect to said latching portions, a connecting link pivotally mounted adjacent one end thereof on the said arm for movement about a pivotal axis disposed in spaced relation with the said first mentioned pivotal axis, the connecting link having means thereon arranged to cooperate with corresponding means on the said counterbalancing means disconnectably to connect the link and the counterbalancing means whereby the counterbalancing means will act normally to urge one of the said latching portions into latching engagement with the keeper means on the frame, the other of the said latching portions being arranged for latching engagement with the keeper means on the sash and having means thereon arranged to cooperate with corresponding means on the sash whereby the said lever member may be operated to cause the said latching portions to engage the said keeper means on the sash and to be disengaged from the said keeper means on the frame respectively, and means on the sash arranged in cooperative relation with the said means on the said latching portion for so operating the said lever member.

2. In a window construction, the combination, with a frame, of a sash mounted in the frame for sliding movement therein, keeper means on the frame and on the sash, sash counterbalancing means mounted on the frame, connecting means for detachably connecting said counterbalancing means with the sash when the same is in a predetermined latch operating position in said frame, said connecting means comprising a support movable in the frame adjacent an edge of the sash, means forming a pivot on the support, a latching lever mounted adjacent an end thereof on said pivot, said lever having oppositely extending latching portions at its end remote from said pivot, anchoring means on said lever spaced from said pivot and connected with said counterbalancing means whereby the counterbalancing means may normally urge said lever member, on said support, in a direction to engage one of said latching portions with the keeper means on the frame and maintain the other latching portion in position to be shifted into engagement with the keeper means on the sash when the same occupies latch operating position, and manually operable means on the sash for engaging and shifting said lever member to release said one latching portion from said keeper means on the frame and to latch the other latching portion with the keeper means on the sash.

3. In a window construction, the combination, with a frame, of a sash mounted in the frame for sliding movement therein, sash counterbalancing means on said frame and means for detachably

connecting said counterbalancing means with said sash comprising a carriage slidable on the frame at an edge of the sash, a latch keeper on the frame and a latch keeper on the sash, means forming a pivot on said carriage, a latch mounted on said pivot and movable thereon to selectively engage the keeper on the frame and the keeper on the sash, means connecting the counterbalancing means with said latch in position spaced from said pivot whereby to normally urge said latch into latching engagement with the keeper on said frame, and manually operable latch actuating means, on said sash, in position to engage and move the latch from engagement with one of said keepers and into engagement with the other of the keepers, when said sash is in a predetermined position in said frame.

4. In a window construction, the combination, with a frame, of a sash mounted in the frame for sliding movement therein, sash counterbalancing means on said frame and means for detachably connecting said counterbalancing means with said sash comprising a carriage slidable on the frame at an edge of the sash, a latch keeper on the frame and a latch keeper on the sash, a latch movably mounted on said carriage, means connecting said counterbalancing means with said latch to normally urge the same in a direction to latch with the keeper on said frame, and manually operable latch actuating means on said sash in position to engage and selectively move the latch from latching engagement with one of said keepers into latching engagement with the other of the keepers.

5. In a window construction, the combination, with a frame, of a sash mounted in the frame for sliding movement therein, sash counterbalancing means on said frame and means for detachably connecting said counterbalancing means with said sash comprising a carriage slidable on the frame at an edge of the sash, a latch keeper on the frame and a latch keeper on the sash, a latch movably mounted on said carriage, means connecting said counterbalancing means with said latch to normally urge the same in a direction to latch with the keeper on said frame, and manually operable latch actuating means on said sash in position to engage and move the latch from latching engagement with one of said keepers and into latching engagement with the other of the said keepers, said frame and sash having facing grooves forming a pocket therebetween for receiving the carriage, and said manually operable means being engageable with said latch only when said carriage is in a predetermined relative position in the groove in said sash.

6. In a window construction, the combination, with a frame member, of a sash member mounted in the frame member for sliding movement therein, sash counterbalancing means on said frame, and connecting means for detachably connecting said counterbalancing means with said sash member, when the same is in a predetermined latch operating position on said frame member, comprising a carriage slidable on the

frame member at an edge of the sash member, keeper means on the frame member and on the sash member, a latch member movably mounted on said carriage, means connecting said counterbalancing means with said latch member to normally urge the same in a direction to latch with the keeper means on one of said members, and manually operable means on the other member in position to engage and move said latch member, when said sash member is in said latch operating position, whereby to release the latch member from the keeper on said one member and to engage the latch member with the keeper on other member.

15 7. In a window construction, the combination, with a frame, of a sash mounted in the frame for sliding movement therein, sash counterbalancing means on said frame and means for detachably connecting said counterbalancing means with said sash comprising a carriage slidable on the frame at an edge of the sash, a latch keeper on the frame and a latch keeper on the sash, a latch movably mounted on said carriage, means connecting said counterbalancing means with said latch to normally urge the same in a direction to latch with the keeper on said frame, and manually operable latch actuating means on said sash in position to engage and move the latch from latching engagement with said keeper on the frame and into latching engagement with the keeper on the sash, said latch having a projecting portion and said manually operable means comprising a bolt movable on the sash, from retracted position thereon, to a projected position adapted to interlock with said projecting portion of the latch, when the sash is moved in the frame to a predetermined latch operating position, said bolt being retractable from said projected position while interlocked with said projecting portion to engage and interlock the same with the keeper on the sash and to disengage the same from the keeper on the frame, said bolt member being also movable from retracted to projected position to release said latch from the keeper on the sash and allow the latch to engage with the keeper on the frame, said bolt being formed to disengage from said projecting portion of the latch upon sliding movement of the sash away from said latch operating position in the frame.
